UNITED STATES PATENT OFFICE

1,936,919

METHOD OF REDUCING THE SHANK
PORTIONS OF SOLES

John Smith, Swampscott, Mass., assignor to
United Shoe Machinery Corporation, Paterson,
N. J., a corporation of New Jersey

Application January 9, 1933. Serial No. 650,803

2 Claims. (Cl. 12—146)

This invention relates to a method of reducing the shank portions of the soles of boots and shoes.

In the manufacture of shoes the outsoles are commonly reduced by making two cuts along the opposite edges of their shank portions so as to provide thin edges at this locality. In the manufacture of certain types of shoes, for example that type in which the outsole is attached permanently to the bottom of the lasted shoe by cement, it is desirable that the opposite edges of all soles of shoes of a given style be reduced to the same predetermined thickness irrespective of differences in the sizes of the sole and that this reduction be accomplished by a production of two bevels which are straight in transverse cross-section. By reducing all the edges to the same thickness, all the shoes of a given style will have the same general appearance in their shank portions. By providing all the soles with bevels which are flat transversely of the soles, all points of such surfaces may be pressed firmly against the similar surfaces on the marginal portions of the lasted shoes, which is important in the attainment of secure attachment of a sole by cement. Hitherto, soles with reduced shank portions approximating the requirements indicated above have been produced, in two operations, by feeding first one side and then the other side of the shank portions of soles past a stationary knife held at the desired inclination to the tread faces of the soles. It is difficult by such a procedure to secure uniform results, and moreover the procedure is a relatively slow one due to the necessity for two separate operations on each sole.

In order to speed up the shank reducing operation, to simplify it, and to make it uniformly accurate, the present invention relates to a method of reducing the opposite edges of the shank portions of soles of different sizes to the same predetermined thickness by straight bevels of the same angular inclination to the tread surfaces of the soles which consists in feeding the soles successively past a knife while progressively holding successive marginal localities in their shank portions bent in converging planes which extend from the longitudinal middle of said shank portions to said opposite edges, and varying the distance of the knife from the middle portions of the soles to provide for soles of different sizes.

Referring to the accompanying drawing where-

use of which the method may be conveniently practiced,

Fig. 1 is a view partly in cross-section and partly in elevation showing a sole of the largest size in process of being operated upon;

Fig. 2 is a cross-section of the finished sole;

Fig. 3 is a view like Fig. 1 but showing a smaller sole in process of being operated upon;

Fig. 4 is a cross-section of the finished smaller sole; and

Fig. 5 is a plan view of a finished sole of the largest size, showing the transverse section on which Fig. 1 is taken.

In the manufacture of shoes of that type in which the soles are permanently attached to the lasted uppers by means of cement, it is customary to apply coats of pyroxylin cement respectively to the margins of the soles and to the margins of the bottoms of the lasted shoes, to permit these coatings to dry, to soften one or both of them, and finally to place the soles on the bottoms of the shoes and hold the soles and shoes under pressure until the cement hardens. In order that a strong bond may be produced between the two coated surfaces, it is necessary that they be pressed firmly into contact throughout their cemented areas. The soles are reduced by being beveled on both sides along their shank portions, as indicated at 7 and 9, so as to produce thin edges. In order that these bevels may be pressed firmly against the bottom of a shoe there should be no hollows in their surfaces, and consequently the bevels should be straight and flat, that is their surfaces should appear as straight lines in transverse section.

In order to facilitate the reducing of the opposite edges, the soles are fed past a knife 11 while successive parts of their shank portions are being progressively held bent as shown in Figs. 1 and 3, and the distance between the knife and the middle portion of the tread surfaces of the soles is varied to provide for soles of different sizes. In the construction illustrated the soles are fed through a matrix formed in a matrix sleeve 13 by the rotation of said sleeve and by the rotation of a feed roll 15 provided with spaced disks 16 the teeth of which may penetrate more or less into the flesh side of the sole. In order to permit the distance of the middle portions of the soles from the plane of the knife to be varied, the matrix sleeve 13, together with its driving shaft 113 and the intermediate sleeve 213, is adjustable vertically toward and from the knife, for example in the manner disclosed in United States patent to

5 Stewart No. 1,382,689. In order that the bevels on the opposite sides of the soles shall have the desired flat surfaces, the walls 17, 19 of the matrix slope straight at the same angles from the bottom 21 of the matrix to the surface of the matrix sleeve, said matrix being made large enough to accommodate soles of the largest size. Inasmuch as large soles are longer than smaller ones and consequently the reduced areas should
10 15 20 25 30 35 40 45 50 55 60 65 70 75 80 85 90 95 100 105 110 115 120 125 130 135 140 145 150

10 vary in length in accordance with the length of the soles, the matrix sleeve is rotated at different velocities according to the lengths of the soles. The feed roll is rotated at constant velocity. For the longest soles the matrix sleeve is rotated at the same peripheral velocity as the feed roll; and for the shorter soles the matrix sleeve is rotated at suitably increased velocities, for example in the manner shown in the patent referred to above, so that the matrix will slip to an extent on the sole in accordance with its increased velocity and the skiving operation will be finished more quickly and will result in shorter reduced portions.

In Figure 1 a sole of the largest size is shown 25 in process of being operated upon, the shank portion being engaged by the feed roll and bent into two converging planes the inclinations of which are determined by the inclinations of the walls 17 and 19. The tread surface of the sole is being pressed against the walls of the matrix, and the skivings are being removed from the flesh side of the sole. When, however, the operation has been completed and the sole, which has been thus progressively distorted is allowed to resume its undistorted condition, a transverse section of it will appear as in Figure 2 in which the grain or tread surface is indicated at 23. Returning to Figure 1, it will be noted that the thickness of the opposite edges of the sole will be equal to the distance along the edges of the sole from the plane of the knife to the adjacent walls of the matrix and that these distances will always be equal to each other since the walls 17, 19 of the matrix converge at the same inclination to the plane of the knife, and the soles are fed centrally through the matrix. Referring now to Figure 3, wherein a smaller sole is shown in process of being operated upon, the matrix sleeve has been adjusted toward the knife until the distances along the edges of this small sole from the plane of the knife to the

adjacent walls of the matrix are the same as those of the larger sole shown in Figure 1. A cross-section of this smaller, narrower sole appears in Figure 4, its opposite edges having the same thickness as the opposite edges of the large sole shown in Figure 2 and its beveled surfaces having the same angles of inclination to the tread face of the sole as do the surfaces 7 and 9 of the large sole.

It is thus possible by this method to reduce the shank portions of soles of shoes of various sizes and of a given style so that their edges will all be of the same thickness and will all be located at the termination of straight bevels which are all of the same inclination to the tread surfaces of the soles; and when soles of shoes of a different style are to be operated upon, it will be necessary merely to change the angles of inclination into which the marginal portions of the soles are progressively bent.

Having described my invention, what I claim as new and desire to secure by Letters Patent of the United States is:

1. The method of reducing the opposite edges of the shank portions of a plurality of soles of different sizes to the same predetermined thickness by straight bevels of the same angular inclination to the tread surfaces of the soles, which comprises feeding the soles successively past a knife while progressively holding successive marginal localities of their shank portions bent in converging planes which extend from the longitudinal middle of said shank portions to said opposite edges, and varying the distance of the knife from the middle portions of the soles to provide for soles of different sizes.

2. The method of reducing the opposite edges of the shank portions of a plurality of soles of different sizes to the same predetermined thickness by straight bevels of the same angular inclination to the tread surfaces of the soles, which comprises feeding the soles successively past a knife while progressively holding successive marginal localities of their shank portions bent in converging planes which extend from the longitudinal middle of said shank portions to said opposite edges, and varying the distance of the knife from the middle portions of the soles in accordance with the widths of the various soles.
